UNITED STATES PATENT OFFICE.

ARON JOHNSON, OF BROOKLYN, NEW YORK.

APPARATUS FOR PACKING COMMINUTED MATERIAL.

Application filed July 1, 1920. Serial No. 393,405.

To all whom it may concern:

Be it known that I, ARON JOHNSON, a citizen of the United States, and a resident of the borough of Brooklyn, in the county of Kings, city and State of New York, have invented certain new and useful Improvements in Apparatus for Packing Comminuted Material, of which the following is a specification.

10 This invention relates to apparatus for packing ground or comminuted material, such as cork mixed with a suitable binder into sticks commonly termed "cork sticks" to constitute a lining material for closure 15 caps of the crown type for receptacles.

In producing this lining material, the crown or comminuted cork with the binder is packed under tamping pressure in tubes into cylindrical form, and after being 20 packed into the tubes is baked to retain the cork in a compact and rigid though yielding mass from which mass portions of predetermined thicknesses are sliced.

It is the primary object of the invention 25 to provide apparatus to pack ground or comminuted cork with a binder into cylindrical form in a novel, more efficient and quicker manner.

In the production of this class of material 30 it is essential that the packed material be substantially of the said consistency throughout, and to attain this result, so far as is known, it has heretofore been the practice to provide a support for a tube or a 35 series of tubes and feed successive increments of material into one end of the tube under pressure, the tube or tubes being successively moved to a series of plungers and the successive plungers being arranged to have a predetermined movement and a 40 tamping pressure applied thereto; and it is a further object of the invention to provide an apparatus in which successive increments of material are fed into opposite ends of 45 the tube or a series of tubes.

It is another object of the invention to provide a carrier for a tube or a series of tubes to position the same with relation to material feeding means, and as the tube 50 or tubes are filled to discharge the same and position another tube or series of tubes relative to the feeding means.

In carrying out the invention I provide a plurality of hoppers or a hopper having a 55 plurality of outlets and arrange pockets at

the hopper outlets, said pockets being arranged in spaced alignment and adapted to receive predetermined quantities of material, with means to shut off and open said pockets to the hopper outlets and regulate 60 the amount of material delivered into the same. Means are provided to support a tube or a series of tubes in horizontal position with the opposite ends thereof in register with the pockets, plungers being operable 65 to deliver the material from the pockets into opposite ends of the tubes as successive increments of material by having a series of movements imparted thereto of successively decreasing extent. Means are provided to 70 intermittently rotate the tube support to deliver the filled tubes from the support and position successive tubes to the feeding means, said means also operating to maintain the support against movement during 75 the periods of rest.

In the drawings accompanying and forming a part of this specification Figure 1 is a front elevation, partly in section, of apparatus illustrating an embodiment of my 80 invention.

Figure 2 is a plan view, partly in section.

Figure 3 is a side elevation.

Figure 4 is an enlarged sectional detail 85 view of the means for feeding material the parts being shown in normal inoperative position.

Figure 5 is a view similar to Figure 4, but showing the parts in material feeding 80 position.

Figure 6 is a sectional end view taken on the line 6—6 of Figure 1 looking in the direction of the arrow of the support for positioning the tubes relative to the feeding 85 means together with means for feeding the tubes to said support and the delivery of the filled tubes therefrom.

Figure 7 is a perspective view of an outlet portion of a hopper.

Figures 8 and 9 are detailed views in perspective of the mounting for a gate to shut off and open the pockets to the hopper outlet and serving as a guide for the material feeding plungers.

Figure 10 is a perspective view of the member arranged at the hopper outlet having material receiving pockets.

Figure 11 is a perspective view of the gate to cooperate with the member shown 100

in Figure 10, operable to shut off and open the material receiving pockets to the hopper outlet.

Figure 12 is a perspective view of means to intermittently move the tube support and showing the manner of maintaining the support against movement during the periods of rest.

Figure 13 is a sectional detail view to 10 show the manner of supporting the tubes at one end in the tube support.

Figure 14 is a perspective view of a reciprocal carriage in which plungers for feeding the material from the pockets into 15 the tubes are mounted.

Figure 15 is a perspective view of the plate removably connected to the ends of the carriage to mount supporting rollers at the ends of the carriage; and

20 Figure 16 is a detail view to show the manner of mounting the carriage supporting rollers upon the carriage.

Similar characters of reference designate 25 like parts throughout the different views of the drawings.

In the embodiment of my invention illustrated in the drawings, a pair of members 16 (Figure 10) are mounted on the projecting ends of rods 23 engaging in openings 24 30 of said members, said rods being mounted in standards 18 and 25 mounted upon a base 19. These members 16 are arranged in spaced relation below hopper outlets 20 which may consist of outlets from a single 35 hopper or a plurality of hoppers, resting upon said members 16 and fastened thereto by screws or bolts passing through perforations in the flanges 21 (Figure 7) of the hopper outlets and threaded into the members 16. The members 16 have a series of 40 pockets 22 in the form of recesses extending transversely of and cut through the top of said members with the bottom wall of circular form. These pockets are arranged to 45 extend in an arc of a circle whose axis lies in the axis of a shaft 17, journaled in a downwardly extending arm of said members 16, and said pockets are adapted to receive material from the hopper outlets, as clearly 50 shown in Figure 4.

As stated, it is an object of the invention to feed successive increments of material into opposite ends of a tube or tubes, and for this purpose a support is provided to 55 support a tube or tubes 26 in horizontal position with the opposite ends thereof in register with the opposed material receiving pockets 22, and from which pockets the material is fed into the opposite ends of the tubes. This support is in the form of a 60 turret comprising a pair of heads 27 fixed upon the shaft 17 in spaced relation, said heads having equidistantly spaced recesses 65 28 (Figure 12) extending around the circumference of the heads to constitute seats

for the engagement of the ends of the tubes and having flanges 29 with perforations 30 to register with the recesses in the heads and openings in the tubes seated in such recesses.

This turret is adapted to be intermittently 70 rotated to successively present a series of six tubes, to be simultaneously filled, one tube being in register with each of the pockets 22 of the members 16. While the present apparatus is designed to present a 75 series of six tubes to be simultaneously filled, it will be obvious that a single tube or a greater or less number than that shown may be positioned to be filled.

The driving means to intermittently actuate the turret to successively present the tubes to the pockets 22 comprises a gear 31 fixed to the turret shaft 17 meshing with a pinion 32 fixed to one end of a shaft 33 (Figure 12) journaled in a bearing member 34 80 mounted on a standard 35 fixed to the base 19. The shaft 33 also has fixed thereto a mutilated pinion 36 with which a mutilated gear 37 is adapted to co-operate to drive the same, said gear being fixed to a shaft 38 85 (Figure 12) journaled in the standard 35 to which a gear 39 is fixed driven from a pinion 40 fixed to a shaft 41, the latter shaft being driven from a suitable source of power 90 by a belt (not shown) passing around a pulley 42 fixed on a shaft 43 journaled in the standards 18 and 25 shown at the right of Figures 1 and 2 by a pinion 44 on said shaft meshing with a gear 45 on the shaft 41. The pulley 42 is coupled and uncoupled from the 95 shaft 43 by clutch mechanism (designed in a general way at 46) thrown into operative and inoperative positions by a lever 47. The ratio of the gearing of the driving means is such that after a predetermined number of 100 successive increments of material have been fed into the tubes the teeth of the mutilated gear 37 will come in mesh with the teeth of the mutilated pinion 36 imparting movement thereto and through the pinion 32 105 and gear 31 transmit such movement to the turret advancing the turret a sufficient distance to deliver six filled tubes from the pockets, and position a succeeding series of six tubes to register with said pockets. 110

The emptied tubes are automatically fed to and the filled tubes delivered from the turret during the movement thereof. For this purpose a hopper (designated in a general way by H) for the empty tubes is fixed 115 to the standards 18 at the front of the apparatus, said hopper having an outlet chute with a support 48 therein for the tubes terminating contiguous to the periphery of the turret heads and the outer wall of the 120 chute between which wall and the support 48 the tubes are guided having the extremity shaped to conform to the curvature of the periphery of the turrets heads and lie continuous thereto, as shown at 49. By this 125 130

arrangement of the outlet chute of the hopper H, the tubes as they are discharged are seated in the turret recesses 28. The filled tubes are delivered from the turret to a discharge chute 50 fixed to the rear of the standards 18, this chute being arranged with the outer end to extend between the turret heads and unseat the tubes from the turret recesses 28 as the turret is revolved and directing the tubes to a suitable receiver for the same.

To deliver the increments of material successively from the pockets 22 into opposite ends of the tubes a series of plungers is provided for each of said series of pockets operable to deliver the material from the opposite pockets simultaneously into opposite ends of the tubes. These plungers comprise rods 51 mounted at one end in carriages 52 to have reciprocal movement therewith upon rods 23. The opposite ends of the rods slidably engage and are guided in perforations 52' formed in guide members 53 mounted upon the standards 18 with the perforations in register with the pockets 22. The carriages are reciprocably mounted upon the rods 23 by rollers 58 to engage at the top and bottom of the rods and journaled on studs 59 threaded into the ends of the carriages and held in position by plates 60 (Figure 15) secured to opposite ends of the carriages.

The pockets 22 are normally open to the hopper outlets to receive material therefrom and to shut off said pockets from the hopper outlets during the feeding of the material from the pockets to the tubes by the plungers and thereby prevent clogging of the material and possibly choking of the material in the opening of the tubes or throw the material from the pockets back into the hopper, gates or valves 54 are provided comprising plates slidably mounted to have movement in guideways formed between the top of the guide members 53 for the plungers and the members 55 (Figure 8) mounted in spaced relation to said guide members 53. The gates 54 are made of relatively thin sheet metal and to prevent distorting of said gates and the consequent wedging thereof in the guideways reinforcing means are provided for the gates within the hoppers and which also serve as guides for the gates in the hoppers, said means consisting of tie rods 92 extending transversely of the hopper in position above the pockets as shown in Figures 4 and 5.

Movement is imparted to the carriages 52 and thereby to the plungers to feed the material from the pockets 22 by levers 56 pivotally supported at one end upon the base 19 and the opposite ends bifurcated and engaging pins 57 extending transversely of a recessed portion in the bottom of the carriages. The carriages with the plungers are

normally maintained in position against buffers 61 of resilient material such as rubber, adjacent the standards 25 by weights 62 carried by cables or straps 63 passing over pulleys 64 and connected to the carriages. Intermittent movement of successive predetermined extent is imparted to the carriages and plungers to feed the material from the pockets 22 as successive increments into the tubes by a cam wheel 65 having a series of irregular cam faces 65^a, 65^b, 65^c, 65^d and 65^e engaged by cam following rollers 66 carried by the levers (Figures 4 and 5). The cams are fixed to shafts 67, journaled in standards 68 mounted upon the base and driven from the shaft 41 by bevelled pinions 69 on said shaft meshing with bevelled gears 70 fixed to the shafts 67 (Figure 2). As the cam wheel 65 is rotated movement of greatest extent will be imparted to the carriages and plungers as shown in Figure 5, and this movement will be successively decreased until the tubes are filled with the material. The plungers are adapted to participate in the reciprocable movement of the carriages and to have longitudinal yielding movement independent of the carriages, and for this purpose are slidably mounted in opposite walls of a recess in the top of the carriages and maintained in position with collars 71 on the plungers in engagement with the forward wall of said recess by springs 72 confined by said collars and the rear wall of the recesses, as clearly shown in Figures 4 and 5.

The gates or valves 54 have a pin and slot connection 73 with levers 74 pivotally supported upon the base and connected by links 75 with levers 76 also pivotally supported upon the base and maintained in position with the pockets 22 opened to the hopper outlet, as shown in Figure 4, by spring 77 and with rollers 78 in engagement with cam wheels 79 fixed on a shaft 67, said cam wheels having a plurality of cam faces and equal in number to the number of cam faces on the cam wheel 65. The cam wheels 65 and 79 are concomitantly rotatable and so arranged and timed that the movement of the gates 54 are slightly in advance of the movements of the plungers to shut off the material receiving pocket 22 from the hopper outlets during the feeding movements of the plungers and open said pockets to the hopper outlets during the receding movement of the plungers.

To adapt the gates 54 to have a variable uncovering movement of the pockets whereby said pockets may receive variable predetermined quantities of material from the hoppers adjustable stops are provided for the levers 74 to limit the outward movement of the gates, and comprising bars 84' extending outwardly from the hopper having a flange 81 to overhang the extended ends of the

levers 74 with set screws 82 threaded in the flanges 81 in the path of the levers 74 and serving as abutments for said levers. It will be obvious that the extent of the uncovering movement of the gates will be in accordance with the adjustment of the set screws 82.

The binder for the cork particles is of a viscous nature and to prevent packing and maintaining such material at the hopper outlets in a loose state to readily fall into and fill the pockets 22 agitating means are provided comprising a pair of curved members 83 and 84 extending through the wall into the hoppers and adapted to have vibratory reciprocatory movements and the portions of the bars within the hoppers arranged with laterally projecting pins 85 to facilitate the agitating of the material. These agitating bars are carried by rockers 86, 87 consisting of laterally extending integral arms connected to opposite ends of the agitating bars and loosely mounted on the shaft 17. The vibratory movement is imparted to the agitators by cams 88 fixed to the shaft 41 operatively connected to the agitators by links 89 pivotally connected at 90 to the rockers 86, 87 and to straps 91 encircling the cams.

In operation previous to starting the apparatus the hoppers 20 filled with material to be packed and the hopper H is filled with empty tubes with a series of tubes carried by the turret in position with the opposite ends in alignment with the outlets of the pockets 22. As the apparatus is set in operation the plunger carriages with the plungers will be given their movement of greatest extent this movement of the plungers being simultaneously in opposite directions, the plungers feeding the material into the opposite ends of the tubes and applying a yielding tamping pressure thereto due to the yielding mounting of the plungers in the carriages. Simultaneously with this movement of the plungers and slightly in advance thereof movement is imparted to the gates 54 to shut off the pockets from the hoppers and thereby assure the feeding of the material from the pockets into the tubes. As the cam following rollers 66 and 78 ride off of a cam portion of the cams 65 and 79 the gates will be returned to position to engage the abutments 82 by the springs 77 and the plunger carriages returned by the weights 62 into engagement with the resilient buffers 61, and these operations of the gates and plungers will be successively repeated with the movement imparted to the plungers of successively decreasing extent until the cams 65 and 79 have made a complete revolution and five movements have been imparted to the plungers and gates when the tubes will be filled with material. At this time the toothed portion of the gear 37 will

come into mesh with the teeth of the pinion 36 and impart movement to the turret moving the filled tubes away from the outlets of the pockets 22 to be discharged by the chute 50, and again positioning a successive series of tubes with the ends in register with the outlets of the pockets 22.

During this movement of the turret empty tubes will be fed from the hopper H to and seated in the turret recesses 28 when the operations are repeated.

Having thus described my invention I claim:

1. In apparatus for the purpose specified, a support for a tube and reciprocable means for feeding successively predetermined quantities of comminuted material into opposite ends of said tube and applying a tamping pressure thereto.

2. In apparatus for the purpose specified, pockets for receiving a predetermined quantity of material, means for supporting a tube with the ends in alignment with said pockets, and means for delivering the material from the pockets as successive increments into opposite ends of the tube and applying a tamping pressure thereto.

3. In apparatus for the purpose specified, pockets for receiving a predetermined quantity of material, means for supporting a tube in horizontal position with the opposite ends in alignment with said pockets, means for delivering the material from the pockets as successive increments simultaneously into the ends of the tube and applying tamping pressure thereto, and means for imparting predetermined movement to said material delivery and tamping means.

4. In apparatus for the purpose specified, a support for a tube, pockets arranged at opposite ends of the tube support in line with a tube carried thereby to receive a predetermined quantity of material, means for feeding the material from the pockets as successive increments of material into opposite ends of the tube, and means for imparting successive variable movements to said material feeding means.

5. In apparatus for the purpose specified, pockets for receiving predetermined quantities of material, movable means to support a tube with the opposite ends in alignment with said pockets, means for delivering material from the pockets as successive increments into opposite ends of said tube and applying tamping pressure thereto, and means for imparting intermittent movement to the tube support to deliver a filled tube from the pockets and move and support another tube in line with the pockets.

6. In apparatus for the purpose specified, means to carry comminuted material with pockets arranged at the outlet of said means to receive a predetermined quantity of material, means to support tubes with the op-

posite ends in alignment with said pockets; and means to deliver the material from the pockets as successive increments into opposite ends of the tubes and applying tamping pressure to such material in the tubes.

7. In apparatus for the purpose specified, means to support a series of tubes in horizontal position; pockets to carry a predetermined quantity of material with which the

10 support is adapted to align the tubes; and plungers operable to deliver material from the pockets into opposite ends of the tubes.

8. In apparatus for the purpose specified, a carrier to support a series of tubes in horizontal position; a series of pockets arranged at opposite ends of the tubes in the carrier and adapted to receive a predetermined quantity of material; plungers slidably supported in alignment with the pockets; and 20 means to impart successive movements of variable extent to the plungers to deliver material from the pockets as successive increments into opposite ends of the tubes.

9. In apparatus for the purpose specified, 25 a carrier for a series of tubes in a horizontal position; pockets arranged at opposite ends of the tubes in the carrier and adapted to receive a predetermined quantity of material to be delivered into opposite ends of the tubes; and means to intermittently actuate the carrier to move the filled tubes away from the pockets and position another series of tubes in alignment with the pockets.

10. In apparatus for the purpose specified, 30 the combination with a pair of hopper outlets, of pockets arranged at the hopper outlets in alignment to receive a predetermined quantity of material; an intermittently rotatable turret to carry and position a series of tubes with the opposite ends in alignment with opposed pockets, plungers slidably supported in alignment with the pockets; and means to impart successive variable movement to the plungers to deliver the 40 material from the pockets into opposite ends of the tubes as successive increments of material and apply tamping pressure to the material in the tubes.

11. In apparatus for the purpose specified, 50 the combination of two series of pockets one series of pockets being in spaced alignment with the other series of pockets; a support to carry a series of tubes in horizontal position in interposed relation to the two series 55 of pockets and with the ends in alignment with said pockets; means with which said pockets are in communication for supplying material thereto; and means to deliver the material from the pockets into the opposite ends of the tubes.

12. In apparatus for the purpose specified, 60 the combination with a plurality of hopper outlets, of a series of pockets arranged at each hopper outlet with the pockets at one outlet in spaced alignment with the pockets

of another outlet; means to shut off and open said pockets to the hopper outlets; a support to carry and position a series of tubes with the ends in alignment with opposed pockets; and means operable to 70 deliver the material from the pockets when shut off from the hopper outlets as successive increments of material into opposite ends of the tubes.

13. In apparatus for the purpose specified, 75 the combination with a plurality of hopper outlets, of a series of pockets arranged at each hopper outlet with the pockets at one outlet in spaced alignment with the pockets of another outlet; a gate for each of the outlets operable to shut off and open said pockets to the hopper outlet; means to regulate the movement of the gate to adapt the pockets to receive variable predetermined quantities of material; a support to carry 80 and position a series of tubes with the ends in alignment with opposed pockets; and plungers slidably supported in alignment with the pockets operable to deliver material from the pockets into opposite ends of the tubes when the gates are in position to shut off the pockets from the hopper outlets.

14. In apparatus for the purpose specified, 85 the combination with a plurality of hopper outlets, of a series of pockets arranged at each hopper outlet with the pockets at one outlet in spaced alignment with the pockets of another outlet; a gate for each of the outlets operable to shut off and open said pockets to the hopper outlet; means to regulate the movement of said gate to adapt the pockets to receive variable predetermined quantities of material; a support to carry and position a series of tubes with the ends in alignment with opposed pockets; and plungers slidably supported in alignment with the pockets; and means to impart variable movements successively to the plungers to deliver the material from the pockets when shut off from 100 the hopper outlets simultaneously into opposite ends of the tubes as successive increments of material and apply tamping pressure to the tubes.

15. In apparatus for the purpose specified, 105 the combination with a plurality of hopper outlets; of a series of pockets arranged at each hopper outlet with the pockets at one outlet in spaced alignment with the pockets of another outlet; a turret to carry a series of tubes in horizontal position with the ends in register with the pockets; means to feed successive increments of material from the pockets into opposite ends of the tubes; and means to 110 intermittently rotate the turret to deliver the filled tubes from the turret and present a successive series of tubes to the pockets.

16. In apparatus for the purpose specified, 115 a turret to support a series of tubes 120

6
in predetermined horizontal position; pockets arranged at opposite ends of said turret to receive a predetermined quantity of material; means for intermittently feeding the material from said pockets as successive increments of material into opposite ends of tubes carried by the support; and means to retain the turret against movement during the filling of a series of tubes and advance the turret after said tubes have been filled to present another series of tubes carried by the support to filling position.

17. In apparatus for the purpose specified, a turret to support a series of tubes in predetermined horizontal position; pockets arranged at opposite ends of said turret to receive a predetermined quantity of material; means for intermittently feeding the material from the pockets as successive increments of material into opposite ends of the tubes carried by the turret and driving means to intermittently rotate said turret a predetermined distance to deliver a series of filled tubes and present another series of tubes to the feeding means including a mutilated pinion and a continuously mutilated gear to co-operate with said pinion.

18. In apparatus for the purpose specified, a turret to support a series of tubes in predetermined horizontal position, comprising a pair of spaced heads arranged with circumferentially disposed seats for the engagement of the tubes; pockets arranged at opposite ends of said turret to receive a predetermined quantity of material; means to intermittently feed the material from the pockets as successive increments of material into opposite ends of said tubes; and means to intermittently rotate said turret predetermined distances to deliver a series of filled tubes and present another series of tubes to the feeding means including the gear rotatable with the turret; a pinion to mesh with said gear, a mutilated pinion rotatable with the first pinion; and a continuously rotating mutilated gear to co-operate with the mutilated pinion.

19. In apparatus for the purpose specified, a plurality of hopper outlets; means to agitate the material at the hopper outlets; a series of pockets arranged at the hopper outlets to receive material therefrom; means to support a series of tubes in horizontal position between said pockets; and means to simultaneously feed the material from said pockets as successive increments into opposite ends of the tubes.

20. In apparatus for the purpose specified, a turret to support a series of tubes in horizontal position comprising a pair of heads arranged with circumferentially disposed seats for the tubes; pockets arranged at opposite ends of the turret to receive pre-

determined quantities of material; means to feed the material from the pockets as successive increments of material into opposite ends of the tubes; means to retain the turret against movement for a predetermined period to fill a series of tubes and to intermittently rotate the turret to present another series of tubes to the filling position; means to feed tubes to the turret during the movement thereof; and means to deliver the filled tubes from the turret during the movement thereof.

21. In apparatus for the purpose specified, a hopper having an outlet; a series of pockets arranged at the hopper outlet to receive a predetermined quantity of material from the hopper; means to support tubes with the ends in register with said pockets; a reciprocable carriage; a series of plungers mounted at one end in the carriage to participate in the reciprocable movement thereof; a guide in which the plungers are slidably supported at the opposite ends to which they are mounted in the carriage and in register with the pockets; said plungers being adapted to deliver the material from the pockets into the tubes; a cam having a series of cam faces; and a pivotally supported lever operatively connected to the carriage carrying a roller to engage with the cam faces.

22. In apparatus for the purpose specified, a plurality of hopper outlets; a series of pockets arranged at each of the hopper outlets in spaced relation and alignment to receive a predetermined quantity of material; means to support a series of tubes with the opposite ends in register with the pockets; reciprocable carriages movable in a direction toward and away from each other; plungers carried by said carriages to deliver the material from the pockets into opposite ends of the tubes; and means to impart successive predetermined movements to the carriages and plungers for the purpose specified.

23. In apparatus for the purpose specified, a plurality of hopper outlets; a series of pockets at each of the hopper outlets in spaced and alignment arrangement to receive a predetermined quantity of material; means to support a series of tubes in horizontal position to extend between two series of pockets with the opposite ends in register with said pockets; carriages mounted to have movement toward and away from the pockets; plungers carried by said carriages to participate in the movement thereof to deliver material from the pockets into opposite ends of the tubes and applying tamping pressure thereto; a pivotally supported lever for each of the carriages operatively connected thereto; and a cam for each lever having a plurality of cam faces to co-operate with the lever to impart variable

successive movements to the carriage and plungers.

24. In apparatus for the purpose specified, two series of spaced and aligned pockets to receive a predetermined quantity of material; a turret arranged to carry a series of tubes with the opposite ends in register with the pockets; a series of reciprocable plungers for each series of pockets; and means to impart a series of movements of successively decreasing extent to the plungers to deliver the material from the pockets into opposite ends of the tubes.

25. In apparatus for the purpose specified, pockets to receive a predetermined quantity of material; means to support a tube in horizontal position with the opposite ends in alignment with said pockets; plungers; and means to impart a series of movements to the plungers of successive decreasing extent to deliver successive increments of material from the pockets into opposite ends of the tube.

26. In apparatus for the purpose specified, two series of spaced and aligned pockets to receive predetermined quantities of material; a turret arranged to carry a series of tubes in horizontal position with the opposite ends in register with the pockets; a series of reciprocable plungers for each series of pockets; means to simultaneously impart a series of movements to the plungers in a direction toward each other and the pockets of successively decreasing extent to deliver successive increments of material from the pockets into opposite ends of the tubes; and means to impart predetermined intermittent movement to the turret and hold the turret against movement during the periods of rest.

27. In apparatus for the purpose specified,

a support for a tube; reciprocable plungers; means to impart a series of movements to the plungers of successively decreasing extent in one direction; and means to impart return movement to the plungers.

28. In apparatus for the purpose specified, means to support a tube in horizontal position; a material receiving pocket arranged at each end of the tube support in line with a tube carried thereby; reciprocable plungers to feed the material from said pockets into opposite ends of said tube; cams having a plurality of cam faces arranged and operable to impart a series of movements of successively decreasing extent to the plungers in one direction; and weights to impart return movements to the plungers.

29. In apparatus for the purpose specified, a container for material to be packed; a support for a tube; means arranged at opposite ends of the tube support in line with a tube carried thereby to receive predetermined quantities of material from the container; and means to deliver and feed said predetermined quantities of material as successive increments simultaneously into opposite ends of the tube.

30. In apparatus for the purpose specified, a container for material to be packed; means to support a tube in horizontal position; means to receive material from the container arranged at opposite ends of the support in line with a tube carried thereby, and means to feed said material as successive increments into opposite ends of the tube.

Signed at Brooklyn, in the county of Kings, city and State of New York, this 29th day of June, 1920.

ARON JOHNSON.
